(57) **CLAIM**

The ornamental design for a jewelry article as shown and described.

DESCRIPTION

FIG. 1 is a front top perspective view of my jewelry article of the present invention.

FIG. 2 is a rear bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

No claim is made to portions of the design which are not shown. The dash-dash lines indicate disclaimed environmental subject matter and form no portion of the present invention. The dash-dot-dash lines indicate claim boundary lines and form no portion of the present invention.

1 Claim, 6 Drawing Sheets
